(57) **CLAIM**

The ornamental design for a plastic bait floating eyeglass retainer, as shown and described.

DESCRIPTION

FIG. 1 is a top plan view of one embodiment of my new design for a plastic bait floating eyeglasses retainer, it being understood that the eyeglasses shown in phantom and the fanciful creature décor, also in phantom, are not part of the design.

FIG. 2 is rear end elevational view thereof; FIG. 3 is a front end elevational view thereof; FIG. 4 is a bottom plan view thereof;

FIG. 5 is a left side elevational view thereof, it being understood that the right side elevational view is a mirror image of the left side.

FIG. 6 is a rear end elevational view of a second embodiment of my new design;

FIG. 7 is a front end elevation view of the second embodiment;

FIG. 8 is a top plan view of the second embodiment, it being understood that the bottom plan view is identical thereto; and,

FIG. 9 is a left side elevational view of the second embodiment, it being understood that the right side elevational view is a mirror image of the left side.
